UNITED STATES PATENT OFFICE.

FRANK K. JOHNSON, OF CHICAGO, ILLINOIS.

ROWBOAT MOTOR.

Application filed February 14, 1927. Serial No. 168,223.

My present invention has reference to hand operated means for propelling and for steering small boats.

An object is the provision of means for this purpose which may be readily attached to the stern of a row boat or like small water craft, and which carries a propeller that is revolved by a handle carrying fly wheel, means within easy access of the operator being provided for reversing the propeller, and a tiller rod also in close proximity to the operator being connected with a tiller or rudder in a novel construction whereby a boat can be propelled in a forward or reverse direction, readily guided or stopped in an easy manner and with a minimum amount of physical exertion.

A further object is the provision of a means for this purpose which shall comprise few simple parts, that may easily and securely be attached to the stern of the boat or removed therefrom, the actuating parts for the propeller being wholly enclosed and the operating mechanism being removable so that the boat cannot be operated except by authorized persons.

To the attainment of the above broadly stated objects and others which will present themselves as the nature of the invention is better understood, the improvement further resides in certain other novel features of construction, combination and operative association of parts, one satisfactory embodiment of which is disclosed by the accompanying drawings.

In the drawings:

Figure 1 is a view of the rear of a small water craft having my improvement attached thereto, the craft being in section.

Figure 2 is a side elevation of the improvement on a somewhat enlarged scale, one of the plates of the casing being removed.

Figure 3 is a detail longitudinal sectional view to illustrate the manner in which the shiftable gears engage with the beveled pinion on the shaft of the propeller.

Figure 4 is a sectional view approximately on the line 4—4 of Figure 2.

Figure 5 is a detail sectional view through the fly wheel to illustrate the manner in which the same is detachably connected with the shaft therefor.

Figure 6 is a detail sectional view to illustrate the connection between the lever and the solid shift rod or shaft.

The back board or stern 1 of a small water craft 2 is illustrated in Figure 1 of the drawings. My improvement is clamped on the stern board 1. The improvement contemplates the employment of a casing 3 that preferably includes a main body portion and a removable face plate 3', the latter being disconnected from the body in the showing of Figure 2 of the drawings. The casing 3 has both of its ends enlarged, the upper enlargement 4 being of a substantially spherical formation and being formed with a hollow inwardly extending hub portion 5. The lower enlargement 6 is of an elliptical formation and is formed with an outwardly directed hub portion 7. In the casing, adjacent to the ends 4 and 6 thereof there are preferably arranged yoke members 8, and between these yokes there are bearing blocks 9 for a hollow shaft 10. The yoke members have their arms connected by bolts 11, and these bolts contact with the outer faces of the bearing blocks 9. Arranged around the hollow shaft 10, and if desired secured to the lower bearing blocks 9 there is a collar 12, and surrounding the said hollow shaft and exerting a tension between this collar and the hub there is a helical spring 14. The wheel 13 has its hub fixed on the elongated sleeve 15 through which the hollow shaft 10 passes. Also fixed on the sleeve 15 there is the hub of a second beveled gear wheel 16 that is arranged face to face with the wheel 13. The hub of the wheel 16 rests on a bearing member 17 which is fixed to the lower end of the hollow shaft 10 by removable means 18. It should be stated that the means that secure the beveled gear wheels 13 and 16 to the sleeve 15 are also in the nature of removable elements. The lower end of the hollow shaft may be closed and the same is received in a cup-shaped bearing 19. Between the bearing 19 and the bearing member 17 there is a race-way and anti-frictional elements 20. The cup-shaped bearing has its lower and closed end provided with a flared depression for the reception of the pointed end of a screw member 21 which is threaded through the lower center of the part 6 of the casing 3, a binding nut 22 being arranged on the screw for holding the same properly positioned. The pointed end of the screw provides a bearing for the member 19 and also serves as an adjusting means for regulating the position of the beveled gears 13 and 16 with respect to

a beveled pinion 23 on the shaft 24 for the propeller 25. The propeller is of the screw type and its shaft 24 passes through bearing blocks 26 similar to the bearing blocks 9, the said bearings 26, however, being arranged in the hub 7 of the part 6 of the casing. Also the shaft 24 preferably passes through a packing box that closes the outer end of the hub 7.

10 The hollow shaft 10 has fixed on its upper end a beveled gear 27 that is in mesh with a similar gear 28 fixed on a shaft 29 that passes through bearings 30 in the hub portion 5 of the upper enlargement or head 4 of the casing 3. The shaft 29 has a reduced outer end which is notched, and this end 31 of the shaft is received through the hub of a fly wheel 32. The end 31 of the shaft has a notch therein, and designed to 20 be received in this notch there is a spring influenced dog 33 that passes through the hub of the fly wheel 32, the shank of the dog being provided with a handle 34. Removably fixed on the fly wheel, adjacent 25 to the periphery thereof there is an operating handle 35. The fly wheel may be readily attached to or removed from the shaft 29, and when removed this shaft 29 cannot be operated nor can the hollow shaft, so 30 that the propeller cannot be operated for propelling the boat. Passing freely through the hollow shaft 10 there is a rod 36. This rod, at the part thereof received in the sleeve 15, has a pin 37 passing transversely 35 therethrough, the said pin also passing through the said sleeve 15. The hollow shaft has elongated openings 38 through which the pin 37 passes. The rod 36 passes through a bearing 39 on the top of the head 40 of the casing 3, the outer end of the rod being provided with spaced flanges, the inner one of which resting on the bearing 39. Arranged on the rod between the mentioned flanges indicated by the numerals 40 there 45 is a ring member 41 that carries an outstanding arm 42 provided with a ball head 43. This ball head is received in a socket 44 in one end of a lever 45. The lever is pivoted, as at 46, to a support 47 on the 50 upper head 4 of the casing 3. It will be apparent that by actuating the lever 45 longitudinal movement will be imparted to the rod 43 so that the same will be moved in an upward direction, and by virtue of 55 such movement will contact with the upper walls of the elongated openings 38 in the hollow shaft 10 and also by virtue of such movement will raise the sleeve to bring the gear 13 out of mesh with the propeller shaft pinion 23 and the gear 16 into mesh with such pinion. When the gear 13 is in mesh with the pinion and the fly wheel turned, the shaft 34 is designed to turn the propeller to move the boat in a forward direction but when the parts are shifted, as

just described, the turning of the fly wheel in the same direction will reverse the turning of the propeller 25 so that the boat will be propelled in a backward direction. Of course, it is necessary that a pressure be 75 exerted on the lever 45 as long as the propeller moves the boat rearwardly.

Journaled in suitable bearings 48 on the outer side of the casing 1, there is the vertically disposed tiller or rudder operating 76 rod 49. The outer end of this rod has a cranked portion provided with a handle 50. To the rod 49 there is connected the rudder 51. The rudder is in the nature of a flat plate and as disclosed by the drawings 80 has its lower edge notched, as at 52, to receive the blades of the propeller 25 therein. The outer portion 53 of the rudder 51 has its end terminating approximately in a line with the axial center of the hub of the 85 propeller 25 or projects slightly therebelow. The rudder thus comprises a comparatively wide member which will effectively contact with the water in properly guiding the boat when the handle 50 is operated. Suitable 90 means may be provided to prevent the free turning of the rod 49.

On its inner face the casing 3 has fixed thereto a vertically disposed arm 54. This arm has its upper end offset to provide a 95 finger 55. The finger 55 is designed to be passed through a socket of the offset end 56 of a jaw member 57. Threaded through the jaw member there is a handle operated screw 58, and this screw enters a threaded 100 opening in an outstanding enlargement 59 in the arm 54. Below the screw, the inner face of the flat jaw 57 is formed with a lug 60. This lug 60 is designed to rest on the upper edge of the stern board, 1, of the 105 boat 2. The jaw it will be noted is loosely connected with the supporting arm 54, it being understood that the screw 58 passes freely through an opening in the jaw, and the hub portion of the handle for the screw 110 contacts with the outer face of the jaw. Thus by turning the screw the jaw will be forced toward its supporting arm 54 to force the said arm against the outer face of the board 1, while the jaw frictionally engages 115 with the inner face of the said stern board. In this manner it will be seen that the device is effectively held from movement in any direction when clamped on the boat.

The simplicity of my construction and the advantages thereof will be perfectly apparent to those skilled in the art to which such invention relates when the foregoing description has been carefully read in connection with the accompanying drawings, 120 but obviously I do not wish to be restricted to the precise details herein set forth and, therefore, hold myself entitled to such changes therefrom as fairly fall within the scope of what I claim.

Having described the invention, I claim:—

1. In a hand operated motor propelled device for small water craft, the combination, a propeller blade having a shaft and a pinion 5 on said shaft, a pair of facing gears arranged on each side of the pinion, a sleeve connecting said gears, a hollow operating shaft passing freely through the sleeve, bearings for the hollow shaft, spring means 10 influencing the connected facing gears to bring one of the same into mesh with the pinion, a rod received through the hollow shaft, and a pin connection between the rod and sleeve that passes freely through the 15 hollow shaft.
2. In a device for the purpose set forth, a tubular casing having enlarged ends, a clamp associated with the casing, a propeller blade having a shaft journaled through the 20 lower end of the casing and a pinion on said shaft, facing gears on each side of the pinion, a sleeve connecting said gears, a hollow operating shaft in the casing and passing through the sleeve, a fixed element on the 25 shaft contacting with the lower gear, a bearing for the lower end of the shaft, an adjustable pivot for the bearing, said hollow shaft having an elongated opening therethrough, spring means influencing the sleeve 30 to bring one of the gears thereon in mesh with the pinion, a rod slidably received in the hollow shaft, a pin on the rod fixing the same to the sleeve and passing through the elongated openings in the hollow shaft, and 35 an operating handle for the rod.
3. In a device for the purpose set forth, a tubular casing having enlarged ends, a clamp associated with the casing, a propeller blade having a shaft journaled through the 40 lower end of the casing and a pinion on said shaft, facing gears on each side of the pinion, a sleeve connecting said gears, a hollow operating shaft in the casing and passing through the sleeves, a fixed element on the 45 shaft contacting with the lower gear, a bearing for the lower end of the shaft, an adjustable pivot for the bearing, said hollow shaft having an elongated opening therethrough, spring means influencing the sleeve 50 to bring one of the gears thereon in mesh

with the pinion, a rod slidably received in the hollow shaft, a pin on the rod fixing the same to the sleeve and passing through the elongated openings in the hollow shaft, an operating handle for the rod, a rudder 55 having a rod journaled in bearings on the side of the casing, and said rudder having a cut-out portion for the passage of the propeller therethrough.

4. A hand operated propelling means for 60 boats, including a hollow casing, a fixed arm on one side of the casing, a jaw member swivelly connected with the arm, adjustable binding means between the jaw member and the arm, a propeller having its shaft journaled through the lower end of the casing and provided with a pinion, facing gears at the opposite sides of the pinion, a sleeve connecting said gears, a hollow shaft journaled in bearings in the casing and passing 65 through the sleeve, a fixed element on the hollow shaft in contact with the lower gear, a bearing for the lower end of the shaft, anti-frictional elements between the bearing and the fixed element, an adjustable pivot 70 for the bearing, a spring surrounding the hollow shaft and exerting a tension against the sleeve for forcing the upper gear in mesh with the pinion, said hollow shaft having an opening at the portion thereof received 75 through the sleeve, a beveled gear on the upper end of the shaft, a laterally extending shaft journaled in the upper end of the casing having a gear thereon in mesh with the last mentioned gear, a handle carrying 80 fly wheel on the last mentioned shaft, means for removably locking the fly wheel on the shaft, a rod passing through the top of the casing and received in the hollow shaft, a pin connecting the rod to the sleeve and 85 passing through the mentioned opening in the hollow shaft, a pivotally supported lever loosely connected with the outer end of the rod, a rudder having a cut-away portion to receive the propeller therethrough, and a 90 handle operated rod for the rudder journaled in bearings on the casing.

In testimony whereof I affix my signature.

FRANK K. JOHNSON.
